UNITED STATES PATENT OFFICE.

ALBERT BALL, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

ELECTRIC CHANNELING-MACHINE.

1,174,223.

Specification of Letters Patent.

Patented Mar. 7, 1916.

Application filed February 2, 1907. Serial No. 355,405.

To all whom it may concern:

Be it known that I, ALBERT BALL, a citizen of the United States, residing at Claremont, in the county of Sullivan and State 5 of New Hampshire, have invented an Improvement in Electric Channeling-Machines, of which the following description, in connection with the accompanying drawings, is a specification, like letters on the drawings 10 representing like parts.

This invention relates to pulsators preferably of the reciprocating type and herein represented as specifically applied to tool actuating motors and associated with improvements in quarrying machines, shown 15 in the present embodiment of the invention as of the channeler type.

In order that the principles of the invention may be fully apparent I have disclosed 20 a single type or embodiment thereof in the accompanying drawings; wherein—

Figure 1 is a side elevation of a channeling machine embodying my invention; Fig. 2 is an end elevation thereof; and Fig. 3 25 is a view mainly in vertical central section of one form of pulsator and working cylinder employed in this embodiment of the invention.

Referring mainly to Figs 1 and 2 of the 30 drawings, wherein a single type of the invention is illustrated, the quarrying body of the machine, herein represented as a channeler, is indicated at 1 and is supported upon suitable wheels 2 that may run upon tracks 35 3. Power may be applied to said wheels in any desired manner as, for example, by means of a separate motor mounted upon the body of the machine, or power may be applied from the main motor in any suitable 40 manner.

In that type of my invention herein illustrated I have chosen to indicate a pulsator for operating the working parts of the machine, although it is apparent that any suitable 45 operating means may be used. In the form of pulsator employed, the fluid, which is preferably compressed air, is supplied to the cylinder thereof upon opposite sides of its piston and from thence is forced to the 50 working cylinder, the air passing in pulsations first from one side of the piston of the pulsator to one side of the piston of the working cylinder and then from the opposite portion of the pulsator to the opposite

side of the piston of the working cylinder. 55 The piston of the pulsator may be operated in any appropriate manner as by an electric motor. A type of such pulsator is indicated in the drawings at 4 and is herein shown (Figs. 1 and 2) as bolted or suitably 60 secured to a swing plate 5 mounted upon the body in suitable bearings as 6, as indicated in Fig. 2, and held therein in any suitable manner as by U-shaped bolts 7.

It is desirable in channelers and other quarrying machines to alter the position of the tools as by movement thereof longitudinally of the machine and also by tilting or rocking the same. While any suitable means may be employed for the purpose, I have 70 herein represented the working cylinder 8 having the piston rod 9, to which the cross head 10 and tools 11 are connected, as mounted upon the standard 12 herein represented as secured by bolts (not shown) 75 passing through slots 13 in the swing plate 5 and preferably, and as herein shown, securing the same upon the face opposite that to which the pulsator is connected. As represented in Fig. 1, the swing plate is provided at different points along its length and preferably at or near the opposite ends thereof with bolt holes and slots so that the standard may be positioned as desired, as for example, upon either side of the pulsator. 80 In order to connect the pulsator and working cylinder, flexible or jointed connections 14 and 15 are employed, herein shown as connecting adjacent sides of the pulsator and the cylinder at top and bottom respectively. In order to permit a change of position of the standard and working cylinder to the opposite side of the pulsator from that represented in Fig. 1 without the employment of longer connections than those 85 shown, the motor and working cylinder are herein indicated as having upper and lower couplings upon both sides thereof. It is therefore possible to change the position of the standard and working cylinder from one 90 side of the pulsator to the other without change in the working proximity of the working cylinder to the pulsator.

Preferably (Fig. 2) a brace 16 or other support is employed to adjust the swing 105 plate in any desired position and to support the same. As herein shown the brace comprises end threaded portions 17 and 18.

suitably secured to the swing plate and the body and a central nut 19. It is apparent that any suitable adjusting means may be employed for this purpose.

For the purpose of adjustably feeding the tools toward or from the work, I have herein indicated a screw 20 suitably secured to the plate 21 bolted to the top of the working cylinder 8 and passing through a suitable bearing in the standard 12. The screw 20 or other cylinder elevating means may be operated by hand or power, but herein for the purpose I have represented a gear 22 having meshing therewith a pinion 23 rotated by a hand wheel 24 (Fig. 2). The feed screw 20 has threaded engagement with a nut held against longitudinal displacement in the overhead arch at the top of the standard, the nut being keyed or otherwise fixedly secured to rotate with the gear 22 and thereby elevate or lower the screw with its attached parts.

The pulsator may be operated in any desired manner. In Figs. 1 and 2 an electric motor 25 is represented as bolted directly to the swing plate 5. A gear 26 thereon meshes with a gear 27 upon crank shaft 28 connected by pitman 29 to the trunk piston 30 (Fig. 3 and dotted lines Fig. 1) of the pulsator. Thereby the piston 31 (Fig. 3) of the pulsator may be reciprocated and the compressed fluid alternately forced to opposite ends of the working cylinder.

In order suitably to build up the air or other fluid in the pulsator any suitable means may be provided. Herein for the purpose is shown a compressor 32 bolted or otherwise suitably secured to the top plate 33 of the pulsator as by the bolts securing said plate to the motor. Mounted within the cylinder of the compressor is a piston 34 having a piston rod 35 passing through a stuffing box 36 and connected to the piston 31 of the pulsator. Any suitable fluid pressure connections between the compressor and the pulsator may be employed. Herein for the purpose is indicated a pressure inlet 37 at the upper portion of the compressor, having a valve 38 normally spring seated and provided with means such as a cam lever 39 for securing or locking the valve open. An outlet passage 40 leads from the upper end of the compressor to the upper end of the cylinder of the pulsator, said passage being controlled by a valve 41 normally spring pressed to its seat and having means such as a cam lever 42 for securing or locking the same open. In the form of pulsator and compressor described, the building up of the air is accomplished by the upward stroke of the piston 34 of the compressor, whereby the air is forced into the upper portion of the pulsator above the piston thereof. A fluid pressure connection 43 leads from the lower portion of the compressor cylinder to

the lower portion of the pulsator and a safety valve 44 normally spring pressed to its seat is provided at any suitable point in the pulsator and is furnished with means, as cam lever 45, for locking the same open.

As previously stated the upper portion of the pulsator is joined by the connection 14 to the upper portion of the working cylinder as indicated at 46 (Fig. 3). By means of an inlet port 47 pressure is admitted from said connection 14 to the upper side of the piston 48 of the working cylinder.

It may be desirable to elevate the piston and thereby the cross head and drills without raising the working cylinder, as for adjustment or change of the tools. While I may employ any suitable means to that end, I have herein shown valved means whereby the fluid pressure entering through connection 14 may be introduced at the lower portion of the working cylinder below the piston 48 therein instead of above the same. In this manner the working piston will be held elevated without interrupting the operation of the pulsator. To effect this result a valve 49 having the handle 49^x is herein shown as rotatably mounted in the head plate of the working cylinder and is provided with a curved passage 50 adapted to be placed in communication with the inlet port 47 or with a passage 51 leading to the working cylinder beneath the piston therein. As herein shown the valve is provided with a vent 52 adapted to register with a vent 53 communicating with the upper portion of the working cylinder whereby when pressure is admitted by means of the passage 51 to the lower side of the piston 48, the pressure that has accumulated above said piston may be discharged. The valve 49 is herein shown as held in position by a suitable valve cap 54.

Viewing Fig. 3 it will be apparent that in the building up of the air in the pulsator air may be forced into the cylinder thereof below the piston 31 by placing the valve 49 in communication with the passage 51, so that pressure may pass from the upper end of the pulsator cylinder through the connection 14 past the valve 50 through the supply passage 51 to the lower portion of the working cylinder and thence by means of the connections 15 to the lower portion of the pulsator cylinder beneath the piston 31 therein.

As indicated in Fig. 3, the cross-sectional area of the compressor cylinder substantially equals that of the trunk piston 30 of the pulsator plus the cross sectional area of the compressor rod 35, so that the compressor piston 34 acting in conjunction with the piston 31 of the pulsator affords a balancing of pressure upon opposite sides of said pulsator piston.

Having thus described one type or embodiment of the invention, I desire it to be understood that although specific terms are used they are employed in a generic and descriptive sense alone and not for purposes of limitation, the scope of the invention being set forth in the following claims.

I claim:

1. A quarrying machine comprising a body and upright support thereon, and a pulsator and working cylinder supported thereby, said pulsator and cylinder being movable relatively to each other lengthwise the machine upon said support. 5
2. A machine comprising a body, an upright plate mounted thereon, a pulsator secured thereto, a standard secured to said plate, and a working cylinder mounted upon said standard and having fluid pressure connections with said pulsator, said standard and pulsator being relatively adjustable upon said plate. 15
3. A machine having a body, a plate mounted thereon, a pulsator secured to one face thereof, a standard secured to said plate upon the opposite face thereof, and a working cylinder secured to said standard and having fluid pressure connections with said pulsator, said standard being adjustable to different positions upon said plate. 25
4. A machine having a body, an upright swing plate mounted thereon, adjusting means for said swing plate, a pulsator mounted upon one face of said plate, a standard mounted upon the opposite face of said plate, and a working cylinder mounted upon said standard, said standard being adjustably secured to either side of said pulsator on said plate. 35
5. A machine having a body, a swing plate mounted thereon, an adjustable brace therefor, a pulsator secured to a face of said swing plate, a driving motor secured to said plate and operatively connected to said pulsator, a standard secured to said swing plate, a working cylinder mounted thereon, fluid pressure connections between said pulsator and said working cylinder, said standard being attachable to said plate at either side of the pulsator, and fluid pressure couplings upon opposite sides of said pulsator and cylinder respectively. 40
6. A machine having a body, an upright plate mounted thereon, a pulsator secured to one face thereof, a standard secured to the opposite face, a working cylinder mounted upon said standard, elevating means for said working cylinder, and fluid pressure connections between said pulsator and said working cylinder, said standard being attachable to said plate at either side of said pulsator. 55
7. A machine having a body, a swing plate mounted thereon, an adjustable brace therefor, a pulsator 5 bolted to said plate, a driving motor 25 bolted to said plate and
8. A machine having a body, a plate mounted thereon, a pulsator 4 fixedly secured to said plate, a standard 12 mounted on said plate, a working cylinder 8 mounted thereon, and fluid pressure connections 14 and 15 between said pulsator and said working cylinder, said standard being adjustable upon said plate with respect to the pulsator. 75
9. A machine having a body, a swing plate 5 thereon, an adjustable brace 16 therefor, a pulsator 4 and a driving motor 25 secured to said plate upon one face thereof, driving connections therebetween, a standard 12 secured to said plate, a working cylinder mounted upon said standard, and fluid pressure connections 14 and 15 between said pulsator and said working cylinder, said pulsator and cylinder having couplings upon 85 opposite sides thereof, and said standard being attachable to said plate at either side of said pulsator. 90
10. A machine having a body, a support thereon, a pulsator and a working cylinder mounted upon said support and having operative connections, said working cylinder being adjustable to position upon said support at either side of said pulsator. 95
11. A machine having a body, a support thereon, a pulsator and a working cylinder mounted upon said support and having operative connections, said working cylinder being adjustable to positions upon said support at either side of said pulsator, and said pulsator having couplings at opposite sides for said connections. 100
12. A channeling machine having a truck, a plate adjustably mounted at the side thereof, a working cylinder adjustable longitudinally from end to end of said plate, a pulsator, and detachable connections between said pulsator and the working cylinder, said connections being reattachable to different outlets in at least one of said cylinders to maintain the same working proximity between the pulsator and the working cylinder when the latter undergoes the said longitudinal adjustment. 110
13. A channeler having a support mounted at the side of the machine and extending substantially the length thereof, a pulsator mounted upon said support and a working cylinder on said support and connected to said pulsator, said cylinder being adjustable 115 to positions on said support at either side of said pulsator. 120
14. A channeling machine having a supporting plate at the side thereof, a motor secured thereto, a pulsator, driving connec- 125
- 65
- 130

- tions between the same and the motor, said pulsator being also secured to said plate, and a working cylinder connected to said pulsator, said cylinder being secured to said plate 5 at either side of said pulsator.
15. A channeling machine having a truck, a working cylinder adjustable from one end to the other thereof, a pulsator, a motor, detachable connections between the pulsator 10 and the working cylinder, said connections being reattachable to different outlets in at least one of said elements to maintain the same working proximity between the pulsator and the working cylinder when the latter is adjusted longitudinally on said truck, 15 while, at the same time, maintaining the said motor fixedly in position.
16. A channeler having a truck, a working cylinder adjustable on said truck from 20 one end thereof to the other, a pulsator, detachable connections between the pulsator and the working cylinder, said connections being reattachable to different outlets in at least one of said elements for maintaining 25 the same working proximity between the pulsator and the working cylinder during adjustment of the latter longitudinally on the truck, while, at the same time, maintaining the pulsator fixed in position.
- 30 17. In a stone working machine, the combination with a supporting member of a pulsator and a working cylinder, the latter being adjustable to opposite sides of the pulsator, and connections between the pulsator and the working cylinder, said connections being attachable on one side of said pulsator in one position of the working cylinder, and on the other side of the pulsator in the other position of the said working 40 cylinder.
18. In a channeling machine the combination with a working cylinder and cutting tools operated thereby, of a pulsator adapted to operate a driven element through said 45 working cylinder by a reciprocating body of air, said pulsator and working cylinder being relatively adjustable, and said pulsator having two exit openings at the same end thereof, and a connection between the working cylinder and the pulsator for attachment to either opening at will, whereby air may 50 be forced through either one of said openings and the same working proximity between the pulsator and the working cylinder 55 maintained during their relative adjustment.
19. In a channeling machine the combination with a working cylinder and cutting tools operated thereby, of a pulsator adapted 60 to operate a driven element through reciprocating bodies of air, said pulsator and working cylinder being relatively adjustable, a plurality of exit openings at each end of said working cylinder, and connections 65 between said pulsator and working cylinder

whereby either exit opening at either end may be opened to the air of the pulsator and the same working proximity between the pulsator and the working cylinder maintained when the two are relatively adjusted. 70

20. In a channeling machine the combination with a working cylinder and cutting tools operated thereby of a pulsator cylinder having at each end circumferentially different exit openings for the air therein, 75 said working cylinder and pulsator cylinder being relatively adjustable, and connections between said cylinders for attachment to either opening to utilize either one at will and thereby maintain the same working 80 proximity between said two cylinders when relatively adjusted.

21. In a channeling machine, the combination with a pulsator, of a tool cylinder, a tool piston therein adapted to be operated 85 by reciprocating bodies of air, a channeling tool connected to said piston, a pair of openings in said cylinder for receiving the air at one side of said piston, said pulsator and tool cylinder being relatively adjustable, and 90 connections between said pulsator and tool cylinder for attachment to either opening, whereby either one may be utilized at will and the same working proximity between the pulsator and the working cylinder maintained when the same are relatively adjusted. 95

22. In a channeling machine the combination with a working cylinder and cutting tools operated thereby, of a pulsator and connecting pipes between the pulsator and working cylinder, said pulsator and working cylinder being relatively adjustable, and means permitting the said pipes to be applied to said pulsator at circumferentially 100 different points thereon whereby the same working proximity between the pulsator and working cylinder may be maintained when the same are relatively adjusted.

23. In a channeling tool, the combination with a truck of a working cylinder with its piston and tool, a standard on which said cylinder is mounted, a support on said truck on which said standard is carried, and a pulsator also on said support, said standard being adjustable thereon relatively to said pulsator. 110

24. In a channeling machine, the combination with a truck of a working cylinder with its piston and tool, a standard on which said cylinder is mounted, an adjustable support on said truck, said standard being itself mounted for adjustment on said support, and a pulsator also on said support, said standard being adjustable thereon relatively 120 to said pulsator.

25. In a channeling machine, the combination with a truck of a working cylinder with its piston and tool, a standard on which said cylinder is mounted, a support on said 130

truck on which said standard is carried, a pulsator also on said support, a driving motor therefor on the support with the pulsator, said standard being adjustable on said support relatively to said pulsator and motor.

In testimony whereof, I have signed my

name to this specification, in the presence of two subscribing witnesses.

ALBERT BALL.
